[57] CLAIM

The ornamental design for a remote control emergency
alarm consisting of a transmitter and receiver, as shown
and described.

DESCRIPTION

FIG. 1 is a top plan view of the receiver of a remote
control emergency alarm consisting of a transmitter and
receiver showing my new design;

FIG. 2 is a front elevational view of the receiver
thereof;

FIG. 3 is a bottom plan view of the receiver thereof;

FIG. 4 is a rear elevational view of the receiver thereof;
FIG. 5 is a right side elevational view of the receiver
thereof;

FIG. 6 is a front elevational view of the transmitter
thereof;

FIG. 7 is a right side elevational view of the transmitter
thereof;

FIG. 8 is a rear elevational view of the transmitter
thereof;

FIG. 9 is a top plan view of the transmitter thereof;

FIG. 10 is a bottom plan view of the transmitter thereof.
